UNITED STATES PATENT OFFICE.

EDWARD E. JOHNSON, OF ST. PAUL, MINNESOTA.

MACHINE FOR GROOVING AND FILLING RODS.

1,358,745.

Specification of Letters Patent. Patented Nov. 16, 1920.

Application filed February 5, 1916. Serial No. 76,253.

To all whom it may concern:

Be it known that I, EDWARD E. JOHNSON, a citizen of the United States, residing at St. Paul, in the county of Ramsey and State 5 of Minnesota, have invented certain new and useful Improvements in Machines for Grooving and Filling Rods, of which the following is a specification.

My invention relates to machines for 10 grooving and filling rods and provides a machine which will mill grooves in rods and fill up the grooves with flux and solder so that the rods may be easily soldered to the insides of well screens for reinforcing the same.

The machine uses coiled wire which is straightened into a continuous rod. This rod is then grooved and the groove filled with solder and flux and the continuous rod 20 is automatically cut off into right lengths to be afterward soldered in place in the well screens to reinforce the same.

The full objects and advantages of my invention will appear in connection with the 25 detailed description thereof and are particularly pointed out in the claims.

In the drawings, illustrating the application of my invention in one form,—

Figure 1 is a front elevational view of 30 my novel device showing a part only of the cut-off actuating elements. Fig. 2 is a rear elevational view of a portion of the machine showing the driving elements including the reduction gearing for the rod feed. Fig. 3 is a plan view of a portion of the machine particularly illustrating the flux reservoir and means for applying the flux to the rod and solder. Fig. 3 and all the succeeding figures are drawn to a larger scale and Figs. 21 to 28 are greatly enlarged.

Fig. 4 is a sectional view of the flux reservoir taken on line 4—4 of Fig. 3. Fig. 5 is a sectional end elevational view of the wire straightening member taken on line 5—5 of Fig. 1. Fig. 6 is an end sectional elevational view of the member for feeding the rod into the machine and is taken on line 6—6 of Fig. 1. Fig. 7 is a front elevational sectional view of the milling head taken on line 7—7 of Fig. 8. Fig. 8 is an end sectional view of the milling head and drive taken on line 8—8 of Fig. 1. Fig. 9 is an end elevational view of the shearing device taken on line 9—9 of Fig. 1. Fig. 10 is an end elevational view of the rod cut-off and rod-ejecting actuating means taken

on line 10—10 of Fig. 1. Fig. 11 is a side elevational view of the cut-off tripping device taken on line 11—11 of Fig. 1. Fig. 12 is a sectional view of the same on line 12—12 of Fig. 11. Fig. 13 is a view similar to Fig. 12 showing the parts in different positions. Fig. 14 is a sectional view of the same taken on line 14—14 of Fig. 13. Figs. 15 and 16 are plan sections taken on lines 15—15 and 16—16, respectively, of Fig. 14. Fig. 17 is an elevational sectional view of the eccentric shaft and parts thereon taken on line 17—17 of Fig. 10. Fig. 18 is an elevational section taken on line 18—18 of Fig. 17. Fig. 19 is a view similar to Fig. 10 of a portion of the device shown therein with some of the parts positioned in different relations. Fig. 20 is an elevational sectional view of the rod-ejecting 75 device taken on line 20—20 of Fig. 1. Fig. 21 is an elevational sectional view showing some of the parts illustrated in Fig. 20 taken on line 21—21 of Fig. 1. Fig. 22 is a view similar to Fig. 20 taken on line 22—22 of Fig. 1. Fig. 23 is a view similar to Fig. 22 with some of the parts in different positions. Fig. 24 is a front elevational view of some of the parts shown in Fig. 21. Fig. 25 is a plan sectional view 85 of some of the parts shown in Fig. 22 taken on line 25—25 of Fig. 22. Fig. 26 is a sectional view of the reinforcing rod after the same has been milled. Fig. 27 is a view similar to Fig. 26 showing the rod completed. Fig. 28 is a view of a portion of a well screen with the rod soldered in place. Fig. 29 is a view of some of the parts shown in Fig. 23 in different relative positions.

The machine as illustrated in the drawings comprises, first, broadly, means for feeding and straightening a large wire from a roll so as to form an extended rod, and for operating upon said straightened rod to 100 load the same with solder as hereinbefore described. These elements are mounted upon a frame member 30 resting on a hollow base 31. A further feature of my invention necessitates the cutting of the filled 105 rod into predetermined lengths while the same is kept in its straightened condition. This involves not only the cutter but guiding mechanism for the rod, actuating means for the cut-off device, and means for operating the guiding means so as to discharge the completed rods. This last mechanism is

supported upon three horizontal members 32, 33 and 34 held in fixed parallel relation by brackets 35 regularly distributed throughout the length of the rods and supported by uprights 36 which are set at suitable intervals and are connected with the central member 33.

The loaded rods are made from stock which is in effect a very large sized wire 37 10 that is supplied by the manufacturer in coils containing several hundred feet of the wire. As shown at the left of Fig. 1, the coils are preferably supported upon a reel 37^A adapted to rotate about a vertical axis. The wire 15 37 passes from the reel 37^A to a straightening device comprising members designated generally as 38 for straightening the wire in one plane and as 39 for straightening the wire in a plane at right angles to the first- 20 named plane. From this point the wire 37 is continuously fed forward as a straight rod 41 by a feeding element designated generally as 40. A continuous rod is fed into a casing 42 containing milling members later 25 to be described, where a longitudinal groove 47 having rounded edges is cut in a straight line along an element of the lower side of the continuous rod. The grooved rod 43 is carried through a guide member 44 having a device which will be later described which enters the groove 47 formed in rod 43 and tends to hold said rod in its fixed straightened position so that the groove will be continuously cut along an element. The rod 30 35 then is fed above a flux-containing receptacle 45 from which a soldering flux is applied to the groove. The solder 46 in the form of wire is fed from a spool at the rear of the milling chamber and into the flux receptacle 45, from which the solder wire is pressed into a groove 47 by a rolling device 49, the loaded rod 50 thereafter being fed through the machine. At 51 the rod is sheared off into proper lengths to be later 40 45 used in reinforcing the well screens 52, as shown in Fig. 28.

The wire straightening device, consisting of elements 38 and 39, is clearly shown in Figs. 1 and 5. Elements 38 and 39 are 50 identical in construction and only differ in their respective locations, as clearly shown in Fig. 1. A casing 53 holds the parts of both members 38 and 39 and terminates in a bracket 54 by means of which it is attached to the casting 30. Each of the elements 38 and 39 comprises a rectangular opening 55 in casing 53 in which is mounted four bars 56, 57, 58 and 59, said bars being shorter than the length of opening 55 and 55 of such a width that all four bars just fill up the width of the opening. To each of these bars is rotatably secured a small grooved roller 60. By means of set screws 61, 62 60 65 screwed into casing 53 and acting against the ends of blocks 56, 57, 58 and 59, said

grooved rollers can be adjustably positioned, and can be rigidly locked in place by means of screws 63 passing through slots 64 in the backs of the respective portions of casing 53 and screwed into said blocks, as best seen in Fig. 5. The wire 37, as seen in Fig. 1, passes alternately over and under each of rollers 60, and when said rollers are brought up against the wire with sufficient force the same leaves the device as a straight rod 41. By loosening either of the end blocks 56 or 59, the rod can be made to have a slight curve which becomes advantageous with hard wire, as a curve is often given this form of wire by the milling cutter and it would hence be just equalized by the method mentioned to secure a straight rod upon leaving the milling cutter.

A feeding device 40 feeds the wire 37 into the machine and is shown in detail in Fig. 6. A base 65 supports two uprights 66 and 67 and is secured to the top of casting 30, as shown in Fig. 1. Each of the uprights 66 and 67 is provided with a vertical tongued slot 68 in which is slidably mounted two grooved blocks 69 and 70. Slots 68 extend into the lower portions of uprights 66 and 67 to crossbars 71 integral therewith and are covered at their open tops by caps 72. The caps 72 are provided with hand screws 73, 95 and the crossbars 71 are provided with set screws 74 for adjusting the relative positions of blocks 69 and 70. Blocks 69 are bored to form bearings for a shaft 75 having a gear 76 at its center and a grooved feed roller 77 at its outer end. Similarly, blocks 70 are bored to form bearings for a shaft 78 have a gear 79 at its center meshing with gear 76 and a grooved feed roller 80 at one of its outer ends to communicate with roller 77. At the other end of shaft 78 is secured a sprocket wheel 83 and a gear wheel 124, the function of which will be later explained. Blocks 69 and 70 in upright 67 may be kept apart by means of a compression coil spring 82, as shown in Fig. 6. Hence by the agency of screws 73 and 74 the rollers 77 and 80 can be made to press upon the rod 41 which passes between them with any degree of pressure, and so cause an effective feed. As only a short relative shift of shafts 75 and 78 is necessary, the drive from one to the other through gears 76 and 79 is effected by employing cycloidal teeth on said gears.

A feeding device 49 almost identical with feeding device 40 causes the solder 46 to be forced into the groove 47 in rod 43 and conducts the finished rod 50 away from the machine. Similar to feeder 40, a base 135 supports uprights 136 and 137. A pair of rollers 138 and 139 are secured on a pair of shafts 140 and 141, respectively, said shafts being slidably adjusted and driven by intermeshing gears 142 and 143 fast on said 130

shafts. On shaft 141 is secured a sprocket wheel 81 by which the device is driven.

The rod 41 upon leaving the feeder 40 enters a milling head 42, shown in Figs. 1, 7 and 8. A box-like housing 84 is adjustably mounted upon a bracket 85 attached to casting 30. This housing is limited to vertical sliding by means of a tongue 86 and a groove, shown in dotted lines in Fig. 7, and by means of a bolt 87 passing through a slot 88 in said housing and screwed into said bracket. Within housing 84 is located a milling cutter 89 secured upon the end of a shaft 90 journaled in bearings 91 and 92, a part of the bracket 85. Milling cutter 89 is driven by means of a belt 94 and a pulley 93 fast on shaft 90. A guide block 95 is set into housing 84 and is normally held in place by a plate 96. This guide block is provided with a guide hole 97 through which the rod 41 passes and exposes its under side of the milling cutter 89. Cutter 89 is hence caused to form the grooved rod 43, shown in Fig. 26, the depth of groove 47 being adjusted by raising and lowering the entire housing 84, as permitted by bolt 87 in slot 88. The front of housing 84 is provided with an opening for access to cutter 89 which is normally closed by means of a cap 98, and the bottom of said housing is open to form a discharge mouth 105 for the cuttings formed therein.

At the bottom of base 31 is located a pump 99 driven by a shaft 100 by means of a belt 101 and a pulley 102 fast on said shaft. The interior of base 31 is hollow and forms a reservoir for the lubricant used in connection with the milling cutter. Pump 99 draws lubricant from this reservoir and forces it through a hose 103 into a nozzle 104 set into the housing 84, as clearly shown in Fig. 7. The lubricant together with the cuttings discharges through the mouth 105 into a suitable receptacle 106 which rests upon a shelf pan 107. The bottom of receptacle 106 is perforated and pan 107 is provided with ducts 108 by means of which the lubricant can flow back again into the previously-named reservoir, thus making the lubricating system automatic and economical.

The groove 47 in rod 43 is formed for the purpose of receiving solder and a proper cleaning flux to clean the surface of the rod and of the portion of the well screen to which it is attached when the solder and flux are heated. This flux is provided in the form of an emulsion somewhat similar in consistency to soft soap. When pressed into the corners of the groove back of the solder wire it will remain in the groove until heat is applied, and being much more easily liquefied than the solder, will flow out over the surface in advance of the

melting of the solder. The solder wire comes in spools 109 which are rotatably mounted upon an arm 110 secured to the front of base 31. The solder wire 46 is led from the spool 109 over and across the bearing head 92 of shaft 90, as seen in Fig. 8, and passes through the receptacle containing flux and into the feeding device 49, where the rod covered with flux is forced into the groove and from which the loaded rod 50 issues. This receptacle 117 is secured to an upright 136 and to the bearing 92 of shaft 90, as shown in Fig. 3. The top of receptacle 117 reaches nearly up to rod 143 and is provided with an extension pan 118 which lies below rod 43 up to where the same enters the feeder 49. Within and at one side of reservoir 117 a shaft 119 is journaled in a bracket 120, and has thereon a pulley 121 and a disk 122. The disk 122 rolls in groove 47 of rod 43 and also in the body of flux within the receptacle, by which means the flux is conveyed to the interior of said groove. The solder wire 46 passes into receptacle 117 under pulley 121 and along the drip pan 118 until it enters feeder 49, where it is forced into the groove 47 of rod 43. It is thus apparent that the interior of groove 47 is first coated with the flux and that the solder wire 46 is also coated with the flux, so that when the solder wire is forced into the groove a considerable quantity of the flux will be trapped in the angles of the groove back of the solder wire, to be released as has been heretofore explained. Ordinarily this method of feeding the flux into the groove will sufficiently agitate the flux. If desired, however, a stirrer may be provided comprising a paddle 230 pivoted to a standard 137 at 231, said paddle extending into the flux reservoir, as indicated at 232, and being engaged and actuated at 233 by a cam wheel 234 fast on shaft 140. It is essential not only that the rod from the spool be properly straightened, but also that the groove in this rod be formed along an element so that when the rods are applied to the inside of a screen tube and the solder-filled groove is secured in contact with the wall of the tube at the end of the rod, and thereafter the rod is forcibly straightened, the solder-filled groove will lie in a straight line in contact with the inner surface of the screen cylinder throughout its length. To insure such a cutting of the groove I provide a sleeve 111 through which rod 43 is fed, as best shown in Fig. 7. Sleeve 111 has a key 112 of a considerable longitudinal extent which fits in the groove 47 of the rod. By means of a handle 113 the sleeve 111 may be rotated in its socket 114 attached to housing 84 by bracket 115, thumb screw 116 securing said sleeve in any required position. In this manner the key 112 can be adjusted so as to be exactly in the line of 130

an element of the straightened rod, and the key operating in the groove of the rod holds the rod as it is fed, so that said groove will continue to be cut along an element of the 5 rod.

The method of driving the feeding devices 40 and 49 is best shown in Fig. 2. The sprockets 81 and 83, heretofore mentioned, are connected by a chain 123. Secured to 10 the shaft 78 on which the sprocket 83 is placed is the gear wheel 124, meshing with a pinion 125 pivoted upon a stub shaft 126 issuing from casting 30. Integral with pinion 125 is a gear wheel 127 meshing with 15 a pinion 128 rotating on a shaft 129 secured in a bracket 130 attached to casting 31. Integral with pinion 128 is a pulley 131 driven through a belt 132. It will be noted that a 20 system of reduction gears is provided whereby a slow speed is given by the feeding devices so that the rate of feed of rod 43 is proportioned to the cutting capacity of the milling cutter 89.

The continuous rod, which is designated 25 as 50, after the same has been loaded with solder and flux as hereinbefore described, must be cut into desired lengths, and this is done without interfering with the feed of the rod or the operations of grooving and 30 filling the same. In a head 134, integral with upright 136, is a guide aperture for rod 50 which is formed at one side with a shearing die 133, the interior of said die forming the aforesaid guide aperture and 35 said die being held firmly positioned by set-screw 144 entering the head 134. A head 145 fast on an eccentric rod 147 which is attached to eccentric strap 148 is adapted to be operated by eccentric 149 on shaft 180. 40 The head 145 is provided with a slot 151 which receives a bolt 150 screwed into head 134 and thereby constrains the head to move in substantially a right line as the same is operated by the eccentric. In the head 145 45 is positioned a shear blade 146 in a slot in head 45 extending obliquely to the line of movement of said head and controlled by set-screw 146^a. The shear blade 146 is thus removable to be sharpened, repaired or replaced and may be accurately positioned for 50 instant cutting effect, and will not be displaced from its slot because the cutting movement is transverse across said slot.

It will be understood that the head 145 is 55 normally out of the path of the rod 50 and is periodically actuated to cut said rod for providing finished rods of a proper predetermined length. The rod 50 must, therefore, be guided beyond the cutter head 145. 60 Such guides are provided by complementary apertures 154 formed by interlocked arms 152, 153, as shown in Figs. 1 and 21 to 25 inclusive. In their normal position, as appears in Figs. 21 and 22, the complementary apertures simply provide a round

guide hole 154. Arms 152 are all secured in alinement upon an ejector rod 32 by means of set-screws 155, and arms 153 are similarly secured upon rod 34 by set-screws 156. Heads 157 on the arms 152 are provided with extensions 159, conical or funnel-shaped as indicated at 158, for causing the rods 150 to be guided into the apertures. From the apertures in heads 157 extend horizontal slots 160, corresponding slots 162 being vertically extended from the apertures in heads 161 on the arms 152. It is to be noted that in the normally closed position the figure outlined by the centers of shafts 32, 34, and of guide opening 154, is 70 an isosceles triangle having the equal sides extending from the centers of shafts 32 and 34, respectively, to the center of guide opening 154. The shafts 32 and 34 have rigidly connected thereto parallel arms 164 and 165 which, in turn, are pivotally connected by a link 166. When rod 34 is periodically oscillated by means hereinafter described it will shift arm 153 and head 161 from the position shown in Fig. 22 to that shown in 90 Fig. 29. By reason of the connection 166 this will simultaneously shift arm 152 and head 158 from the position shown in Fig. 22 to that shown in Fig. 29, where the rod 50 is released from the closed aperture 154 and is 95 free to drop out of the machine through vertical slots 162 and is positively ejected therefrom. Tongue portions 163 on heads 161 enter slots 160 in heads 157 when the parts are in closed position and coöperate 100 with the flared portion of head 157 to complete the conical guide openings 154.

Below the ejector arms 152 and 153 is situated a trough 167 supported on brackets 168 mounted on the uprights 36, as best 105 shown in Figs. 1 and 20. This trough extends the whole length of the receiving and ejecting portion of the machine and serves to receive the rods after they leave the ejector arms 152 and 153. 110

The shear previously mentioned is actuated automatically to cut off the rods in given lengths in a manner now to be described. Parallel with rods 32, 33 and 34 is a smaller rod 169 slidably mounted in 115 regard to the device in lugs 170 issuing from the castings 35 and extending the whole length of the machine. Rod 169 is positioned in close proximity to the rod 50 and to a scale 171 attached to the tops of lugs 120 170. Adjustably secured to rod 169 by a thumb screw 172 is a pointer 173 having at its lower end a projecting target 174 resting in the path of travel of rod 50. As rod 50 is forwarded by the feeders 40 and 49 said 125 rod engages target 174 and shifts rod 169, which automatically engages a clutch, setting the shear in action in a manner now to be explained. When the sheared portion of rod 50 has been ejected rod 169 is re- 130 135

stored to its normal position by means of a spring 175 acting between a collar 176 on said rod and an adjacent supporting casting 35.

5 The form of clutch used for operating the shear, which clutch however may be of any desired kind, is best shown in Figs. 10, 17, 18 and 19. A bracket 179 issuing from the rear of casting 31 rigidly supports a stub shaft 180 held in place by a set screw 181. A sleeve 182 is free to rotate about shaft 180 and has cast integral with it at one end a cam 183 and is held in place on shaft 180 by means of a head 184 on said shaft. On 10 sleeve 182 adjacent cam 183 is rotatably mounted a pulley fly-wheel 185 continuously driven by a belt 186. Between pulley 185 and the bracket 179 are rigidly secured on sleeve 182 the eccentric disk 149 of the shearing device and a brake drum 187 rotatable within a brake band 188 secured to casting 31 at 189. The wheel 185 continuously rotates upon sleeve 182 and the brake thus provided prevents sleeve 182 from rotating 15 until the clutch member is engaged. The clutch used is of a well-known form and is best seen in Fig. 17. The bearing surface of pulley 185 is provided with an axial semicylindrical slot 190, and sleeve 182 at its contact surface with pulley 185 is provided with a corresponding semicylindrical slot 191 which extends through cam 183 as a cylindrical hole 192. Within hole 192 is a short round rod 193 ground off at 194 to completely fill slot 191 and provided at its cylindrical end with an arm 195 rigidly riveted thereto. This rod is held in place by means of a cap 196 screwed in place on cam 183. Cap 196 is provided with apertures 197 and 20 198 through which both ends of arm 195 project and allows rod 193 to have a small amount of oscillatory motion. The upper end of arm 195 is held toward the right by means of a spring 199 and in this position 25 tends to thrust a shoulder 200 of rod 194 into slot 190 whenever that slot passes said rod, thus tending to engage the pulley 185 with the sleeve 182 for rotation in the direction indicated by the arrow in Fig. 10. An arm 177, 30 pivoted at its center upon a bracket 201 secured to casting 31, has a finger 202 which engages the lower portion of arm 195 as the sleeve 182 is rotated and serves to disengage pulley 185 from sleeve 182, and also to cause 35 said sleeve to stop at a precise predetermined point. An arm 203 secured to rod 34 is equipped with a cam roller 204 which is held into engagement with cam 183 by a spring 216. By this means rods 32 and 34 are given 40 their oscillatory motion for ejecting the cut-off portions of rod 50. It will be noted that cam 183 is so constructed that the ejecting takes place after the rod has been sheared.

In combination with the aforementioned 45 rod 169 is a tripping device which raises

lever 177 to disengage finger 202 from clutch arm 195 to actuate the clutch for operating the shear and ejectors. This device is shown in Figs. 10, 11, 12, 13, 14, 15 and 16. Arm 177 is stopped by a bumper 205 and is pivotally connected to a vertical rod 178. Rod 178 is pivotally secured to a square slide 206 operating in a housing 207 attached to the rod 33 by means of a lug 208 and a set screw 209. As seen in Figs. 12 and 15, slide 206 70 is normally held in a downward position by means of a latch dog 210 engaging with a portion of the top thereof and pivoted within housing 207 at 212. Dog 210 is held in place by a compression coil spring 211, 75 and when the same is withdrawn it allows slide 206 to move upward and engage the clutch, as shown in Figs. 13 and 19. A horizontal slide 213 is rigidly secured to rod 169 and carries at its center a catch lever 214 80 normally held in engagement with lever 210 by means of a flat spring 215, as clearly shown in Figs. 14 and 15. As the rod 169 is shifted by the moving rod 50, lever 210 is withdrawn by the catch 214 and the clutch 85 actuated. Slide 206 is restored to its normal position by means of a plunger 217 within housing 207 which is lowered by an arm 218 and a pin 221, said arm being secured to rod 32, as best seen in Fig. 11. As cam arm 203, 90 referring to Fig. 10, commences to rise, following cam 183, the arm 218, due to the parallel link motion shown in Fig. 20, commences to lower and to restore slide 206 to its normal position. As, however, the rod 100 50 has not yet been sheared or ejected, the slide 213 is held out and the lever 210 is hence held from engagement with slide 206 when the same shall have been restored. To free lever 210 at this time from catch 214 105 said catch and plunger 217 are provided with cam surfaces 219 and 220, so that as the plunger 217 is lowered the catch 214 is receded within slide 213 from engagement with lever 210, as best seen in Fig. 14. This 110 expedient, however, does not interfere with the return of slide 213 at any time when the sheared portion of rod 50 shall have been ejected. As plunger 217 again travels upward catch 214 once more comes in engagement with lever 210 prior to cutting off another portion of rod 50. It will be noted that the sleeve 182 makes only a single revolution each time and that the parts remain 115 in the original position at the end of that 120 revolution. The shearing action, as noted from the fact that pulley 185 is directly driven, takes place so quickly that rod 50 has not been appreciably advanced before the shear block 145 is out of the way. By 125 adjusting pointer 173 any length of rod may be cut off. In Fig. 1 only a portion of the receiving end of the machine is shown, as the same may be made as long as desired depending upon the length of rod to be cut. 130

I claim:

1. A machine for grooving and filling rods comprising means for feeding the rods and cutting a straight groove therein as fed, a source of supply of solder in the form of a continuous wire, and means for feeding and forcing said solder wire into the groove as the rods are fed. 70
2. A machine for grooving and filling rods comprising means for feeding the rods and cutting a straight groove therein as fed, a source of supply of solder in the form of a continuous wire, a receptacle containing a viscous flux through which said wire passes, and means for feeding and forcing said solder wire into the groove as the rods are fed. 75
3. A machine for grooving and filling rods comprising means for feeding the rod, means for straightening the rod as the same is fed, means for cutting a straight groove in the rod after the rod is straightened, and means for filling the groove with solder. 80
4. A machine for grooving and filling rods comprising means for feeding the rod, means for straightening the rod as the same is fed, means for cutting a straight groove in the rod after the rod is straightened, and means for filling the groove with solder and for applying a flux to the solder before the same is introduced in the groove. 85
5. A machine for grooving and filling rods comprising means for continuously feeding an extended rod, means for cutting a straight groove in the rod as the same is fed, means for filling the groove with solder, and means for cutting the rod into predetermined lengths while the same is being fed. 90
6. A machine for grooving and filling rods comprising means for feeding the rods and cutting a straight groove therein as fed, means for introducing a soldering flux into the groove, and means thereafter for filling the groove with solder. 100
7. A machine for grooving and filling rods comprising means for feeding the rods and cutting a straight groove therein as fed, a source of supply of solder in the form of a continuous wire, means including a receptacle containing soldering flux for introducing said flux into the groove, means thereafter for feeding and forcing said solder wire into the groove as the rods are fed. 105
8. A machine for grooving and filling rods formed from a continuous roll of large wire comprising means for feeding the wire, means for straightening the wire as the same is fed, means for cutting a groove in the rod formed of the straightened wire, and means for filling the groove with solder. 110
9. A machine for grooving and filling rods formed from a continuous roll of large wire comprising means for feeding the wire, means for straightening the wire as the same is fed, means for cutting a groove in the rod formed by the straightened wire, means in- 115
- cluding an elongated key entering into the groove for guiding said rod so that the same will be held from twisting and the groove be formed straight along an element of the rod, and means for filling the groove with solder. 70
10. A machine for grooving and filling rods formed from a continuous roll of large wire comprising means for feeding the wire, means for straightening the wire as the same is fed, means for cutting a groove in the rod formed by the straightened wire, means including an elongated key entering into the groove for guiding said rod so that the same will be held from twisting and the groove be formed straight along an element of the rod, means for filling the groove with solder, and means for cutting the filled rod into predetermined lengths while the same is being fed. 80
11. A machine for grooving and filling rods comprising means for feeding the rod, means for straightening the rod as the same is fed, a milling cutter operative in a fixed plane, means for guiding the rod so that said cutter will be caused to cut out a groove in the rod, a key held in fixed position and entering into said groove to hold the rod from twisting and cause the groove to be cut in a straight line along an element of the rod, and means thereafter for filling the groove with solder. 90
12. A machine for operating upon rods comprising means for straightening and continuously feeding an extended rod, means for cutting a straight groove in the rod and filling the same with solder as the rod is fed, and means controlled in operation by the movement of the rod to cut the rod in predetermined lengths. 100
13. A machine for operating upon rods comprising means for straightening and continuously feeding an extended rod, means for cutting a straight groove in the rod and filling the same with solder as the rod is fed, means controlled in operation by the movement of the rod to cut the rod in predetermined lengths, and means simultaneously operative to discharge said lengths of rod from the machine without terminating operation of the feeding means. 105
14. A machine for operating upon rods comprising means for straightening and continuously feeding an extended rod, means for cutting a groove in the rod as fed, means for filling the groove with solder, means thereafter for guiding the rod in a fixed pathway, means for cutting the rods in predetermined lengths, and means for actuating said guiding means when the rod is cut to discharge said lengths from the machine. 110
15. A machine for operating upon rods comprising means for feeding the rod, means for straightening the rod as the same is fed, means including a housing having a chamber therein and an aperture extend- 120
- 65
- 125
- 130

- ing through the chamber for guiding the straightened rod so that the same passes through the top of said chamber, a milling cutter in the chamber extending into the 5 path of the rod, and means for operating the cutter to cause the same to cut a groove in the rod as the same is fed.
16. A machine for operating upon rods comprising means for feeding the rod, 10 means for straightening the rod as the same is fed, means including a housing having a chamber therein and an aperture extending through the chamber for guiding a straightened rod so that the same passes 15 through the top of said chamber, a milling cutter in the chamber extending into the path of the rod, means for operating the cutter to cause the same to cut a groove in the rod as the same is fed, and means for injecting fluid upon the cutter and into the 20 groove.
17. A machine for operating upon rods comprising means for feeding the rod, means for straightening the rod as the same is fed, a housing for guiding the straightened rod, and a milling cutter operative 25 within the housing to cut a straight groove along an element of the rod.
18. A machine for operating upon rods comprising means for feeding and straightening the rod, means for cutting a groove in the rod, and an elongated key held in fixed position and entering said groove to hold the rod from twisting and causing the 35 groove to be cut in a straight line along the element of the rod.
19. A machine for operating upon rods comprising means for feeding and straightening the rod, means for cutting a groove 40 in the rod, an elongated key held in fixed position and entering said groove to hold the rod from twisting and causing the groove to be cut in a straight line along the element of the rod, and means for adjusting 45 the key.
20. A machine for operating upon rods comprising means for feeding and straightening the rod as the same is fed, means for cutting a groove in the rod, a tubular guide 50 for said rod through which the rod extends after the groove is cut, and a key in said tubular guide entering said groove to hold the rod from twisting and causing the groove to be cut in a straight line along an 55 element of the rod.
21. A machine for operating upon rods comprising means for straightening and continuously feeding an extended rod,
- means for cutting a straight groove in said rod, means for filling the groove with 60 solder, means for guiding the filled rod, a cutting member associated with part of said guiding means, and means set in operation by movement of the rod for actuating said cutting member to cut the rod into predetermined lengths while the rod is being fed. 65
22. A machine for operating upon cylindrical rods comprising a cutter, means on each side of the cutter operable upon the rod for feeding the same so that the cutter 70 will cut a groove in the rod, and means for holding the rod from turning while the groove is cut.
23. A machine for operating upon rods comprising means for feeding a rod, means 75 for straightening the rod as the same is fed, a housing for guiding the straightened rod, a milling cutter operative within the housing to cut a straight groove along an element on the underside of the rod, and means 80 for injecting fluid into the housing and upon the cutter and into the groove.
24. A machine for operating upon rods comprising means for feeding and straightening the rods, said straightening means 85 being operative to give the rod an upward camber in a vertical plane, a milling cutter operative to cut a groove in the lower portion of said rod in said vertical plane and tending to produce a camber in the opposite direction, and means for guiding the rod to and past the cutter while the same is fed. 90
25. A machine for grooving and filling rods comprising means for feeding the 95 rods and means for cutting a straight groove therein as fed, a receptacle containing soldering flux, a disk operative within said flux and in the groove for introducing the flux in the groove, and means thereafter 100 for filling the groove with solder.
26. A machine for grooving and filling rods comprising means for feeding the rods and means for cutting a straight groove therein as fed, a receptacle containing 105 soldering flux, a disk operative within said flux and in the groove for introducing the flux in the groove, means thereafter for filling the groove with solder, and means for agitating the flux within the receptacle. 110

In testimony whereof I affix my signature in presence of two witnesses.

EDWARD E. JOHNSON.
